UNITED STATES PATENT OFFICE.

JOHN T. HUGHES, OF COUNCIL BLUFFS, IOWA.

VALVE HANDLE.

Application filed May 21, 1924. Serial No. 714,802.

To all whom it may concern:

Be it known that I, JOHN T. HUGHES, a citizen of the United States, residing at Council Bluffs, in the county of Pottawattamie and State of Iowa, have invented certain new and useful Improvements in Valve Handles, of which the following is a specification.

The present invention relates to valves, 10 and more particularly to valve handles.

In globe and gate valves considerable difficulty has been experienced in the application and use of handles because such handles have heretofore been constructed of 15 castings, which at best are rough and do not fit properly upon the valve stems, and which are costly in the casting and subsequent finishing operations.

Among various other difficulties met with 20 in the manufacture, application, and use of valve handles, has been that the handle is connected to the valve stem at substantially a single point, so that when considerable pressure is exerted upon the handle to turn 25 the same, the stem, being engaged at a single point, is not capable of withstanding the strain and is frequently sheared off or broken at the handle.

It is therefore an object of this invention 30 to provide a handle which overcomes at least the two above pointed disadvantages, in that the handle may be constructed of sheet metal and made in two die operations, and wherein the handle engages the stem at 35 spaced apart points so as to distribute the pressure of the handle and prevent the shearing off or breaking of the stem.

Another object of the invention is to provide a handle structure embodying the above 40 characteristics and which may be of conventional size and form so as to be adaptable to the valve stems which are now in use and without any alteration or addition to the same.

A still further object of the invention is 45 to provide a sheet metal handle adapted to engage the upper part of a valve stem, and which is equipped with a boxing or brace arranged to engage the thicker and more 50 substantial portion of the stem, and be interlocked with the handle at points spaced from the outer extremity of the stem, the parts being held in assembled relation by the usual clamping nut employed with valve 55 handles at present in use.

The above and various other objects and

advantages of this invention will be in part described in, and be in part understood from, the following detailed description of the present preferred embodiment, the same 60 being illustrated in the accompanying drawing, wherein:

Fig. 1 is a side elevation of a globe valve having the improved handle applied thereto, the handle being shown in section. 65

Fig. 2 is a detail top plan view of the body of the handle.

Fig. 3 is an edge view of the boxing or brace of the handle detached therefrom.

Fig. 4 is an end elevation of the brace, and 70

Fig. 5 is a top plan view of the same.

Referring to the drawing, 10 designates a valve body of any approved construction, such as a globe or a gate valve, and which is provided with a valve stem 11 which projects through the top of the casing 10 and is adapted to receive a handle or other suitable device for turning the stem and opening and closing the valve. 75

The improved handle comprises a sheet 80 metal body part 12, which may be stamped to provide a flat disc like major portion and a downwardly curved flange 13 providing a suitable hand grip to facilitate grasping of the handle and holding it firmly when turning the same. The disc portion of the handle 12 may be stamped out to provide openings 14 to reduce the weight of the handle and also for ornamental purposes. The central or intermediate portion of the 85 handle 12 is provided with a non-circular opening 15 adapted to receive the correspondingly shaped upper end of the valve stem 11, such upper end being usually rectangular in contour and tapering upwardly for a considerable distance to form a square shank 16 upon which the handle is mounted. The upper end of the shank 16 is provided with a threaded extremity or stud 17 over 90 which a clamping nut 18 is threaded for engagement against a washer 19 adapted for direct contact with the top of the handle 12 to force it downwardly upon the tapering shank 16. 95

The handle 12 carries at its underside a 105 boxing or brace 20 which is substantially U-shaped in edge elevation as shown in Fig. 3, and which has its opposite ends upturned to provide arms 21 which space the intermediate portion of the brace 20 away from the top of the handle 12, the intermediate portion of the brace 20 having a relatively 110

large non-circular opening 22 therein which is adapted to receive the larger intermediate portion of the shank 16 and to assist the handle 12 in turning the stem 11.

5 The upper ends of the arms 21 are cut away at the corners to provide tongues 23 which are of less width than the arms 21 to form shoulders 24 upon which the handle 12 is adapted to seat. The handle 12 is provided 10 with elongated slots 25 at opposite sides of the non-circular opening 15. The slots 25 receive the tongues 23 so as to interlock the brace 20 with the handle. When the nut 18 is turned down on the stud 17 it binds 15 the handle 12 against the shoulders 24 of the brace and not only interlocks the brace and handle but also forces the shank 16 up into the openings 15 and 22 of the handle and brace. Torsional strain on the stem 11 20 is therefore distributed over the spaced area of the shank 16 so that the pressure is applied at a thicker portion of the stem than is usual and the upper extremity of the stem which is relatively thin is not subject to the 25 entire pressure of the handle.

It is of course understood that various

changes and modifications may be made in the details of construction and design of the above specifically described embodiment without departing from the spirit of the invention, such changes and modifications being restricted only by the scope of the following claim:

What is claimed is:

A valve handle comprising a sheet metal 35 disc having an intermediate non-circular opening and having elongated slots at opposite sides of the opening, a U-shaped brace having a non-circular central opening and upturned ends having reduced tongues 40 thereon adapted to fit in said slots of the disc, said brace and disc being adapted to fit in spaced relation upon the stem of a valve, and means for binding said disc and brace together and for binding the same 45 upon the valve stem.

In testimony whereof, I have affixed my signature in presence of two witnesses.

JOHN T. HUGHES.
